UNITED STATES PATENT OFFICE.

ALEXANDER H. WILSON, OF CHICAGO, ILLINOIS, ASSIGNOR TO THOMAS ELEVATOR COMPANY, OF CHICAGO, ILLINOIS, A CORPORATION OF ILLINOIS.

HOISTING MACHINE.

Application filed March 1, 1922. Serial No. 540,098.

This invention relates to improvements in hoisting machines, more especially such as are designed primarily to be operated by an electric motor and are provided with reversing devices whereby the hoisting drum or sheave may be rotated in either direction or may be maintained idle while the motor is continuously operating in one direction, the chief object of such a construction being 5 to avoid the necessity of reversing the motor every time the direction of rotation of the winding or hoisting element of the machine is to be reversed.

A hoisting machine of the type to which 15 my present invention belongs, and upon which my present invention is in the nature of an improvement, is disclosed in Letters Patent to W. A. Barker No. 736,572, dated August 18, 1903. In the machine of the 20 said patent there is disclosed a hoisting drum and a grooved cable-driving sheave, the former being used for simple hoisting operations, while the latter is employed to operate alternately a pair of elevating platforms or carriers which travel simultaneously in opposite direction. In the said patent both the drum and the sheave are permanently fast with the drum-shaft so that they rotate simultaneously. One object of 25 my present invention is to provide a mechanism by which either the drum or sheave may be operated, the other remaining idle, which secures greater independence of function. A further object is to provide an improved mechanism whereby when either the 30 drum or the sheave is placed in driven relation to the shaft, the other is held against rotation.

Still other objects and advantages of my 35 present invention will be apparent to persons familiar with hoisting machines of this character from the following detailed description, taken in connection with the accompanying drawings wherein I have fully 40 illustrated a hoisting machine embodying my present improvements in one practical and approved form and in which—

Fig. 1 is a side elevational view of a hoisting machine embodying my present improvements;

Fig. 2 is a top plan view of the same;

Fig. 3 is a central vertical sectional view 55 through a pair of twin motion reversing devices that are interposed between the drive-shaft of the motor and the drum-shaft of the

machine and through which the direction of rotation of the latter and its starting and stopping are controlled;

Fig. 4 shows in face and side elevations one of a pair of stationary cam members 60 fixed to the frame of the machine and operating the clutch devices of the intermediate reversing shafts;

Fig. 5 is a view similar to Fig. 4 showing one of a pair of oscillatory companion cams 65 designed to co-operate with said stationary cams in operating the clutch mechanism;

Fig. 6 is a side elevational view of the clutch operating lever, showing also the connection therefrom to a pivoted latch which 70 holds the brake mechanism in working position when both clutches are disengaged;

Fig. 7 is an enlarged vertical section taken on the lines 7—7 of Fig. 2; and

Fig. 8 is a fragmentary side elevation, 75 partly in vertical section of the clutch and brake mechanism controlling the drum and sheave.

Referring to the drawings, 10 designates a platform or base-plate, and 11 and 12 a pair of parallel standards, carrying a pair of superposed pillow blocks 13 and 14 (Fig. 3), in which are rotatably journaled a pair of companion shafts 15 and 16, respectively. On the standard 11 and another parallel 80 standard 17 are a pair of pillow blocks 18 and 19, respectively, in which is journaled a drum-shaft 20. Keyed on the shafts 15 and 16 are a pair of intermeshing companion gears 21 and 22, these gears having fast on 85 corresponding faces thereof internally bevelled collars 23 and 24 constituting female members of a pair of friction cone clutches. Mounted to rotate loosely upon the shafts 15 and 16, respectively, are a pair of sleeves 90 or bushings 25 and 26, fast on which are mounted hubs 27 and 28, to the inner faces of which hubs are bolted or otherwise secured fibre male cone clutch members 27' and 28', while to the outer faces of said hubs 100 are similarly secured gears 29 and 30. Loosely mounted on the shafts 15 and 16 are also a pair of externally threaded bushings 31 and 32, mounted on which to turn therewith are a pair of collars 33 and 34. 105 The outer annular faces of said collars are formed with a pair of diametrically opposite cam points or elevations, such as are shown 34^a, 34^b in connection with the collar 34 in Fig. 5, it being understood that the 110

collar 33 is provided with a similar pair of cam projections. Secured to the inner faces of the pillow blocks 13 and 14 are a pair of collars 35 and 36, respectively, the inner 5 annular faces of which are provided with diametrically opposite cam points or projections, such as 36^a and 36^b, Fig. 4, designed for co-operation with the corresponding cam points of the collars 33 and 34 to effect the 10 engagement of the respective clutch members 27', 23 and 28', 24 respectively, in the manner hereinafter described. The collars 35 and 36 are adjustably secured in fixed position relatively to the pillow blocks to 15 which they are attached by means of clamp bolts 37 and 38 engaged with arc-shaped slots formed in segmental extensions 39 and 40 depending from the lower edges of said collars.

20 Fast with the collars 33 and 34 are radial arms 41 and 42, respectively, (Fig. 1) terminating in segmental racks 43 and 44, respectively, through the actuation of which in the manner hereinafter described said 25 cam faced collars 33 and 34 are oscillated simultaneously to produce opposite movements of the upper and lower male members of the clutches. Journaled in the standard 11 midway between the clutch shafts 15 and 16 is a short rock-shaft 45 (Fig. 6), on the inner end of which is a segment gear 46, which meshes with both of the segment gears 43 and 44. Fast on the outer or opposite 30 end of the shaft 45 is an operating lever 47 terminating at its upper end in a handle 47^a. Secured to the outer face of the standard 11, opposite the bearing of the shaft 45, is a fixed quadrant 48 having a central notch 48^a, with which co-operates the lower end 35 of a locking rod 49 mounted to slide vertically in a guide lug 50 on the inner face of the lever 47, the upper end of this rod being pivoted to the lower end of a release lever 51 pivoted to the main lever 47. The locking 40 rod 49 is provided, just above its lower end, with a lateral extension 49^a, which passes through a vertical slot 47^b formed in the lever 47. Thence the lateral extension 49^a is continued in the form of a vertical 45 depending extension 49^b, which passes through a guide lug 52^a projecting from and connecting the opposite sides of a divided housing or guide 52 also fast on the outer end of the shaft 45 and partially embracing 50 the lower end portion of the lever 47. On the lower end of the extension 49^b is a pin 49^c, on which is hung a bent rod 53, the lower end of which is secured to a latch-bar 54, pivoted at its inner end at 55 to the pillow block 13, the outer end of said latch-bar 54 having a hook 54^a adapted to co-operate with a shoulder on a foot-operated brake-lever as hereinafter described. The pin 49^c is so situated as to be in line with the center 55 or axis of the rock-shaft when the rod 49 is

raised out of engagement with the notch of the quadrant as hereinafter described.

57 (Fig. 2) designates an electric motor, the armature shaft 57^a of which carries a pinion 58 meshing with the gear 21. Gears 29 and 30, constituting elements of the sliding male clutch members, both mesh with a large gear 59 keyed to the drum-shaft 20. Integral or otherwise fast with the large gear 59 is a brake wheel 60. Loose on the 75 shaft is a winding-drum 61, and also loose on said shaft is a stepped grooved cable-driving sheave 62. Co-operating with the brake wheel 60 is a brake comprising a pair of brake shoes 63 (Fig. 1) mounted on the 80 ends of a yoke 64 which latter in turn is centrally seated on a brake-lever 65 that is pivoted at one end at 66 to a block 67 on the base 10 and at its other end rests upon the short arm 68 of a lever 69 that is sleeved 85 on a shaft 70 mounted in and between the standards 11 and 12 (Fig. 2). Pivoted on one end of the shaft 70 is a foot lever 71 that is adjustably connected to the lever 69 by a clamp bolt 72 extending through an 90 arc-shaped slot 73 in the lever 69. The inner end of the foot lever 71 is upwardly and reversely curved, as shown in Fig. 1, and terminates in a shoulder or hook 71^a that co-operates with the hook 54^a of the arm 95 54. A compression spring 74 maintains the engagement of the hooks 54^a and 71^a and, when said hooks are disengaged, acts to throw the foot lever upwardly and simultaneously release the pressure on the brake. On the adjacent faces of the drum 61 and sheave 62 are a pair of clutch members 75 and 76, respectively, between which is a double faced clutch member 77 that is splined on the drum-shaft 20, as best shown 100 in Fig. 8. This slidable clutch member 77 is encircled by a strap 78 carrying lateral pins 79 that are engaged by the slotted arms of a forked clutch shifting lever 80. This latter is fast at its lower end on a rock-shaft 105 81 journalized in a pair of bearings 82. Fast on one end of the rock-shaft 81 is an upwardly extending clutch shifting lever 83 terminating in a handle 83^a (Fig. 7). By shifting the lever 83 in one direction the 110 drum 61 is made fast with the shaft 20 while the sheave 62 is simultaneously disengaged from the shaft, and by shifting the lever in the opposite direction the sheave 62 is engaged with the shaft and the drum 61 115 120 is simultaneously disengaged. When the lever is in its central or intermediate position, both the drum and the sheave are freed from the shaft.

It is desirable that when either the drum 125 or the sheave is thus clutched to the shaft the other shall be held stationary. This result is effected simultaneously with the shifting of the clutch and through the movements of the clutch shifting lever 83 by the mech- 130

anism best shown in Figs. 7 and 8, wherein it will be seen that the periphery of the sheave 62 and the periphery of the adjacent head of the drum 61 are disposed directly above a pair of brake shoes 84 and 85, respectively, which are carried by arms 86 and 87 pivoted at their outer ends to lugs 88 on the base 10. The brake shoes are normally raised into braking engagement with the sheave and drum by strong compression springs 89 underlying the free ends of the brake arms 86 and 87. Fast on the shaft 81 is a yoke 90 (Fig. 8), the ends of which overlie the brake arms 86 and 87. In the central or intermediate position of the clutch shifting lever 83 the yoke 90 is horizontal and depresses both of the arms 86 and 87 sufficiently to disengage the brake shoes from the drum and sheave. When, however, the clutch is shifted to connect the sheave 62 with the drum-shaft, the brake 84 of the sheave is depressed and the brake 85 of the drum is released and instantly applied to the latter. When the lever is shifted to connect the drum to the shaft, the brake shoe 85 is depressed and the brake shoe 84 is released and instantly engages the sheave. It will thus be seen that the instant either the drum or sheave is clutched to the shaft, its brake is locked in release position and the brake of the other is applied. At 91, I have indicated an ordinary electric controller through which the current is supplied to and cut off from the motor 57.

The machine herein shown and described is adapted to be employed as a simple hoisting machine in a great variety of situations where hoisting operations are required, in which cases the hoisting drum 61 is used, the operating cable being wound and unwound thereon in a manner common in all hoisting machines employing a cable receiving drum of this sort. The machine is also extensively used to operate material elevators in connection with the erection of buildings where a pair of elevating platforms or carriers are employed and so connected to

the hoisting apparatus as to travel simultaneously in opposite directions. In such cases a driving cable is passed one or more 50 times around the sheave 62 and attached at its opposite ends to the two elevating platforms or carriers respectively.

The operation of the machine is believed to be fully evident from the foregoing description of its structure and organization, and from the disclosure it will be apparent that I have modified and improved the hoisting machine of the patent hereinabove referred to to obtain greater flexibility and 60 enable the machine to be employed to drive either the winding drum or cable sheave, according to the particular job in hand, independently of the other, and at the same time locking the other in place, which is 65 sometimes desirable, where the two operations may be alternately performed with greater or less frequency on one and the same job.

I claim:

In a hoisting machine, the combination with a driving shaft, and power-actuated mechanism for rotating said shaft, of a pair of cable-winding elements both loose on said shaft, driven clutch members on the opposed faces of said elements, a driving clutch member splined on said shaft between said driven clutch members, a rock-shaft, a clutch shifter fast thereon engaged with said driving clutch member to shift the latter between said driven clutch members, an operating handle fast on said rock-shaft, pivoted arms carrying brake shoes engageable with the peripheries of said cable-actuating elements, springs urging said arms in a direction to engage said brake shoes with said cable-actuating elements, and a transverse yoke fast on said rock-shaft and at its ends overlying said arms and operating, when said handle is swung in either direction, to 90 retract one of said brake shoes and permit the other to be applied by its spring.

ALEXANDER H. WILSON.
